(57) **CLAIM**

The ornamental design for a folded locker bin, as shown and described.

DESCRIPTION

FIG. 1 is a perspective view of a folded locker bin showing my new design;

FIG. 2 is a front view thereof;

FIG. 3 is a back view thereof;

FIG. 4 is a left side view;

FIG. 5 is a right side view;

FIG. 6 is a top plan view;

FIG. 7 is a bottom view;

FIG. 8 is a top plan view of the folded locker bin in an unfolded, blank condition; and,

FIG. 9 is a top plan view of the inner holder of the folded locker bin in an unfolded, blank condition.

The broken lines are understood to represent the fold lines used to construct the blanks into the folded locker bin.
